UNITED STATES PATENT OFFICE.

SAMUEL K. STINGER, JR., AND HARRY K. ROBINSON, OF PHILADELPHIA, PENNSYLVANIA.

MEANS TO ELECTRICALLY CONTROL STREET-SWITCHES.

1,025,545.

Specification of Letters Patent.

Patented May 7, 1912.

Application filed September 20, 1911. Serial No. 650,471.

To all whom it may concern:

Be it known that we, SAMUEL K. STINGER, Jr., and HARRY K. ROBINSON, both citizens of the United States, residing at the city of Philadelphia, in the county of Philadelphia and State of Pennsylvania, have invented certain new and useful Improvements in Means to Electrically Control Street-Switches, of which the following is a specification.

Our invention relates to means to electrically control shifting of street turnout switches by a motorman from the car; and in such connection the invention relates to the constructive arrangement of such means electrically controlled by manually operating levers from the car to cause the switch-tongue to be shifted and thus to control the course of the car at turnouts, without having to stop the same.

The nature and scope of our present invention will be more fully understood from the following description taken in connection with the accompanying drawings forming part hereof, in which,

Figure 1, is a top or plan view of a section of a road-bed, showing a crossing and turnout having a shiftable switch and electrical means manually actuated from the car by a motorman to shift the switch, embodying main features of our present invention. Fig. 2, is an enlarged transverse sectional view on the line $x-x$, of Fig. 1, and showing in broken section the car platform, the spring controlled contact disks and the electro-magnets and armatures for controlling shifting of the switch from the car by the motorman; and Fig. 3, is a diagram, showing the arrangement of the switch circuits in a branch of the controller car circuit, and the switch and mechanical parts to permit of shifting the course of a car, without stopping the same.

Referring to the drawings a^1 and a^2 , are track-rails mounted on a road-bed a .

a^3 , is a crossing having a turnout provided with an ordinary tongue-switch a^4 .

b and b^1 , are current distributing rails located inside of the track-rails.

b^2 , represents the platform of the car. Depending therefrom and secured thereto, are U-shaped brackets k and k^1 , in which brackets are mounted spring controlled vertical foot-plungers b^4 and b^5 , having at their lowered ends contact disks b^6 and b^7 . These

disks, by depressing either of the said plungers are adapted to make sliding contact with the contact rail b or b^1 , located between the track-rails a^1 and a^2 , to energize an electro-magnet and thereby shift the switch-tongue a^4 . On the foot-plungers b^4 and b^5 , are secured stops b^8 , and b^9 , within and beneath the supporting brackets k and k^1 , for the springs b^{10} and b^{11} , surrounding said foot-plungers, as clearly shown in Fig. 2, in order thereby to limit the extent of movement of the said foot-plungers.

d and d^1 , are the electro-magnets located in a concrete or similar casing d^2 , underneath the road-bed a , as clearly shown in Fig. 1.

d^3 , is a lever-arm suspended from the switch-tongue and carrying armatures d^4 and d^5 , for the electro-magnets d and d^1 .

When either foot-plunger b^4 or b^5 , is depressed under the tension of the springs b^{10} and b^{11} , coiled around the same, a contact disk b^6 or b^7 , will make contact with the current distributing rail b or b^1 , and a current will pass through one of said electro-magnets d and d^1 , to thus cause the switch-tongue a^4 , to be shifted into required position to permit the car to pursue its regular course beyond the turnout, or to pass around the turnout of the cross-over section of the road-bed, without having to stop the car.

In Fig. 3, in diagram, is shown the overhead trolley line 5, which by a pole and line 6, is connected to a circuit breaker h , of the car b^2 , thence by the line 7, controller 8, and line 9, to one brush e , of the motor E , and thence by the other brush e^1 , of the motor E , and line 10, to ground g . The line 6 is shunted from the circuit breaker h , by the lines 12, 12^a and 12^b, to the foot-plungers b^4 and b^5 . The current distributing rails b and b^1 , by the lines 13 and 14, are connected to the electro-magnets d and d^1 , and the circuit therefrom is continued to either ground g^1 or g^2 . When the foot-plunger b^5 , as indicated in dotted outline in Fig. 2, is pressed into contact with the rail b^1 , the current from the main line 5, through the car is shunted from the circuit breaker h , through the line 12, without affecting the controller car circuit 8, so as to energize the electro-magnets d^1 , when one of the armatures of said electro-magnets will be attracted to the electro-magnet to thus cause the switch-

tongue a^4 , to be shifted to the position as shown in Fig. 3, permitting thereby, the car, without stopping at a cross-over of the road-bed a , to continue its regular course 5 beyond the turnout. Through the depressing of the foot-plunger b^4 , in a manner as above explained, a similar result, in an opposite position of the switch-tongue a^4 , can be obtained, thus causing the car upon 10 reaching the cross-over to change its course over the road-bed.

Having thus described the nature and object of our invention what we claim as new and desire to secure by Letters Patent is:—

15 In combination, tracks having a tongue-switch, two electro-magnets, a lever-arm located between said magnets and in connection suspended from said switch, the lower end of said lever-arm carrying the armatures 20 of said magnets, an electric circuit, contact

rails located adjacent to said track-rails and included in said circuit, brackets secured to the under side of the car-platform, foot-plungers mounted in said brackets and having springs, said foot-plungers provided with stops within and beneath said brackets to control in conjunction with said springs the extent of movement of said foot-plungers and the latter provided with disks adapted to make sliding contact with said 25 contact-rails.

In witness whereof we have hereunto set our signatures in the presence of the two subscribing witnesses hereto.

SAMUEL K. STINGER, JR.
HARRY K. ROBINSON.
